UNITED STATES PATENT OFFICE

EDGAR HÖNIG, OF BERLIN, GERMANY

BUILDING FOR INDUSTRIAL PURPOSES

Application filed November 25, 1930, Serial No. 498,147, and in Germany December 2, 1929.

The present invention relates to buildings, and more particularly to buildings for industrial purposes.

In its specific form the invention relates to that type of building in which provision is made for the more or less continuous conveyance of goods, as in warehouses, garages or factories in which the article under production is manufactured in successive stages and for this purpose is conveyed, for example by means of conveying belts or other suitable transport means from one shop to another.

In buildings of this kind it has hitherto been usual to build up the different floors in one block, and to provide inclines or approaches leading from the one story to the next and situated at the centre of the building, or to dispose the different floors, which are also connected by inclines or approaches, in step-like fashion about a central point.

These arrangements are accompanied by the disadvantage that, for example in the case of factories, either the raw material is introduced at the bottom of the building and the finished article emerging at the top requires to be conveyed again to the ground floor by special transport means, or special transport means are required to convey the raw material to the top of the building, so that the finished article will emerge at the bottom.

In the case of garages the provision of central approaches or inclines takes up a very large amount of space owing to the limited turning capability of the cars, in addition to which special approaching ramps are also required; or the cars require to be turned round again to descend to the ground floor, travelling in an opposite direction to the ascending cars and accordingly necessitating a double width of track to enable the cars to pass, so that in this case a very considerable amount of space is also wasted.

According to the invention, the upward track and the downward track are disposed in different parts of the building, and these parts are caused to cut each other at one

or more points. In this manner the following advantages are obtained.

1. It is possible on any floor to change over at the cutting point from upward to downward movement in direct fashion. 55

2. The upward and downward movements take place in separate parts of the building.

3. By the provision of additional wings to the building separate manufacturing processes are also rendered possible. 60

4. The paths of the upward and downward movement are identical with the actual tracks, so that no waste of area occurs in connection with the elevation.

5. The raw material may be introduced on the ground floor, while the finished article emerges on the same level. 65

6. By the total disposition the greatest safety is offered against fire, as each floor may be made to close off in fireproof fashion 70 against the next without presenting any obstruction to the way of escape.

7. The number of manufacturing stages or the total manufacturing process may be increased by building on additional floors 75 or new wings, without necessity for reorganizing the whole run.

The invention will now be described more fully with reference to the accompanying drawings, in which 80

Fig. 1 is the plan view of a possible form of embodiment of the new type of building according to the invention,

Fig. 2 being a section of the same building 85 in perspective view.

Fig. 3 is the plan view of another form of embodiment, while

Fig. 4 shows the generation of the different floors.

Referring now to the drawings, the ascent 90 commences on the ground floor at the point designated A. The goods or articles being conveyed are taken along an incline *a* up to the level B, which is disposed for example 4½ feet above the ground floor A. The ascent then continues along a second incline 95 *b* up to the level C which, following the same dimensions, is situated, say, 9 feet above the ground floor. An additional incline *c* then leads to the level D, which is 100

situated, for example, $13\frac{1}{2}$ feet above the ground floor.

The ascent may be continued from this point to any desired extent. If necessary, 5 however, the goods or articles may also be conducted over an incline α down to the level X, which is situated 9 feet above the ground. The further descent then proceeds over an incline γ to the level Y ($4\frac{1}{2}$ feet 10 high) and finally over an incline β to the level Z, which is the ground floor again.

As an alternative the upward and downward tracks may also be disposed as in Fig. 15 3, in which these are indicated by the arrows.

It will be understood that no restriction is made to the specific forms of embodiment shown, and that various modifications are quite possible within the meaning of the 20 above description and the annexed claim without departing from the spirit of the invention.

What I claim as new and desire to secure by Letters Patent is:

25 A building equipped for progressive transport along the different floors and from one floor to the other of goods under manufacture, storage and the like, comprising sections of substantially spiral form, the 30 spirals being of similar turn in the same direction of travel of an object but of opposite turn in different directions of travel of an object, with the spirals intersecting to provide a part common to both, each of 35 the spirals being made up of horizontal portions interrupted at determinate points by inclined ramps connecting such horizontal portions.

In testimony whereof I have affixed my 40 signature.

EDGAR HÖNIG.
